POWER PLANT

John Riise, Doylestown, Ohio

Application January 27, 1937, Serial No. 122,541

7 Claims.

(Cl. 60—97)

The object of this invention is an improved power plant suitable for driving well drilling machinery. Time and expense necessary for erection in the field are the two important factors to be considered and both are greatly reduced. In addition, the trouble due to misalignment is avoided by my construction.

The combination of independent power units and jackshaft units with a bed structure defining by its assembly the position and orientation of each unit with reference to the other units is an essential feature of the invention.

The means for adjusting and locking the power units upon their bed members are also important in facilitating the assembly of the plant.

The arrangement of independent jackshafts in approximate axial alignment with an intermediate connecting shaft, which is supported at its ends by two flexible universal joints, is an important element of my invention.

Another feature is the provision of a spare engine which can be held in reserve or used as a substitute for or in combination with either or both of the other engines.

Fig. 1 is a plan view showing one embodiment of my invention.

Fig. 2 is a sectional view showing the construction of the intermediate shaft as indicated in Fig. 1 and its connection with the jackshafts.

Fig. 3 is a plan view of the bed structure with one power unit supporting frame in position.

Fig. 4 is a plan view corresponding to Fig. 3, showing a power unit in place.

Fig. 5 is a side elevation of Fig. 4 and includes the jackshaft. In order to show details of construction, a part of the bed member is broken away.

Fig. 6 shows a cross sectional elevation taken on plane 6—6 of Fig. 3.

Fig. 7 is an enlarged vertical partial section on plane 7—7 of Fig. 5 through the power unit supporting frame and its bed member.

Fig. 8 is a plan view of a modification of my invention in which the spare engine is operatively connected to an intermediate shaft in axial alignment with the jackshafts.

Fig. 9 is a plan view of another modification of my invention in which the spare engine is operatively connected to an intermediate shaft in parallel-offset relation to the jackshafts.

Fig. 10 is an elevation showing the end view of Fig. 9.

Fig. 11 is a section through one of the sliding clutches of the intermediate shaft of Fig. 8, taken on plane 11—11 of Fig. 8, and shows a method of

supporting the intermediate shaft upon the jackshaft by a self aligning bearing.

Fig. 12 is a plan view of an assembled plant of another modified form.

Fig. 13 is a side elevation of one of the units with part of the bed structure and framework angles broken away.

Fig. 14 is a plan view showing means for effecting transverse adjustment of a power unit on its bed structure.

Fig. 15 is a cross sectional elevation of Fig. 14, taken on plane 15—15 of Fig. 14.

Fig. 16 is a plan view of the bed structure with additional bracing members.

Fig. 17 is a cross sectional elevation taken on plane 17—17 of Fig. 16.

Fig. 18 is a sectional view of one of the intermediate shafts and its connection to the jackshafts.

In the figures:

In Fig. 1, the power unit 20 comprises a prime-mover 25, a transmission 26 which may have multiple forward speeds and a reverse, a cross shaft enclosed in a housing 27 and having keyed upon its outer end a driving pulley 28. The power unit is mounted upon a supporting frame 29, the combination forming a unit capable of being dragged about. This assemblage is termed the engine bed.

The spare power unit 30 is preferably a duplicate of unit 20.

The power unit 31 may be a duplicate of the other two; but, as its work is normally driving the pumps which do not require low speed or reverse drives, a one speed transmission 38 may be used.

The power unit 20 is operatively connected to the jackshaft 33 through a belt mounted on the pulley 28 and on a free pulley 34 connected to the shaft 33 by the dog clutch 35. A sprocket 36 is keyed to the shaft 33 and has driving connection with the sprocket 37 mounted on the hoist 38. Power is transmitted to the drill rig (not shown) through driving means 39, which consists usually of a chain.

The power unit 30 is shown in Fig. 1 as being operatively connected to a jackshaft 42 through a free pulley 40 and a clutch 41.

The power unit 31 is similarly connected to the jackshaft 42 through a free pulley 43 and a dog clutch 44. The jackshaft 42 carries two free sprockets, one of them at the end, numbered 45 and 46, which may be locked to the shaft by clutches 47 and 48. The sprocket 45 is operatively connected to the drive pump 49 and the

sprocket 46 is connected to a drive pump 50 by means of a chain and sprocket.

Between the jackshafts 33 and 42 is an intermediate shaft assembly 51 which has a flexible driving connection (universal joints) with the jackshafts, capable of operating under a limited degree of misalignment.

Fig. 2 shows in section the construction indicated in Fig. 1. An externally toothed member 52 is keyed to the shaft 42 and a similar member 53 is keyed to the shaft 33. The internally toothed member 54 engages the externally toothed member 52 with sufficient looseness to allow the desired amount of axial divergence between the shafts, so as to form a universal joint. Keyed to the member 54 is a stub shaft 55, shown turned down at the end to receive the bearings 56, 56. A sliding clutch member 57 has a splined engagement with the stub shaft 55 and is shifted by a collar 58 and by suitable levers (not shown). Jaws on the clutch 57 engage jaws on a quill shaft 59 and an enlarged end 60 of a hollow shaft 61 is internally toothed and engages the member 53 in a manner similar to that in which members 52 and 54 form a universal joint. Retaining rings 62, 62 are bolted to the internal toothed members 54 and 60 preventing undue end motion of these parts and providing a chamber for the lubricant. The quill shaft 59 and the hollow shaft 61 are preferably made separate and attached together by flanges 63, 63' for ease in production and to allow of changing the length of the assembly.

The jackshafts 33 and 42 are carried by self aligning bearings 65, 65 on pedestals 66, 66. These pedestals are bolted to the bed angles 67, 67 and 68, 68 (see Fig. 1) so that each jackshaft assembly, with its bed structure, forms a unit and is therefore transportable as a unit and requires no alignment service within itself.

In erecting a plant the two jackshaft units are brought into approximate axial alignment and connecting angles 69 and 70 are bolted in place, insuring correct spacing and satisfactory alignment. Bed members 71, 71 for the power units are then bolted to the jackshaft bed members by corner angles 72 providing a track automatically spaced and squared upon which the power unit is slid. End angles 75, 76 are bolted in place and connecting angle 77 is bolted to them, insuring that vibration of the power plant will not shift the bed members. Belt connection with the jackshaft is made, proper belt tension is established by a tension rod 73 and perfect belt and pulley alignment is secured by the jacks 74 at each corner of the power unit frame (Fig. 7).

The intermediate shaft is telescoped enough to allow it to be slipped into place, the retaining rings 62 are bolted on and the power plant is erected.

The connection of spare power unit 30 with the jackshaft 42 precludes its use to drive the hoist, draw works and drill rig at a variable speed 65 while the pumps are being driven at a constant speed. It cannot effectively substitute for power unit 20 while the pumps are running.

An arrangement in Fig. 8 is shown in which the spare power unit drives an intermediate shaft 82 through a free pulley 80 and a clutch 81. The shaft 82 is connected to jackshafts 83 and 84 by clutches 85 and 86 and is mounted upon shafts 83 and 84 by a self aligning bearing at each end, as shown in Fig. 11.

75 An intermediate shaft 99 may also be disposed

in offset parallel relation to jackshafts 100 and 101, as shown in Figs. 9 and 10 and operatively connected to the jackshafts through sprockets 90 and 91, keyed to the intermediate shaft, and sprockets 92 and 93 mounted on the jackshafts 5 and adapted to be connected therewith by clutches 94 and 95. The spare power unit may be connected to drive the intermediate shaft 99 through a pulley 98, which may be connected to the jackshaft by means of the clutch 97.

With either of these constructions, the spare power unit may take the place of either of the other power units, or may combine its power with either or both of the power units. When joined with or substituting for power unit 20, 10 it can use any speed or reverse, while unit 31 15 is free to drive the pump and when joined with or substituting for power unit 31, unit 20 is left free to drive the drill rig at any speed or reverse. Spare unit 30 may also be held in 20 reserve while the other two units work either singly or combined.

In Fig. 12 power unit 110 comprises a prime mover 111, a transmission 112, which may have multiple forward speeds and a reverse, a cross shaft housing 113, a driving pulley 114 and a jackshaft 115 having a free pulley 116, which may be connected to the shaft 115 by a clutch 117. These units are mounted on a framework 118, making an assembly which may be transported as a unit. A sprocket 119 is keyed upon the shaft 115 and has a driving connection with the sprocket 120 on the hoist 121, to which the drilling rig may be connected.

The jackshaft 115 is journalled in self aligning 35 bearings 122 in pillow blocks 123 (Fig. 18), which are adjustable, means 190 are provided mounted upon the frame 118 to enable the proper belt tension to be readily obtained. The entire power unit is adjustable transversely and longitudinally 40 upon bed members 124, 124 by threaded rod 125 and wedges 126, 126 at each corner of the frame (Fig. 14). Threaded member 127 is secured to the end angle 150 by a single pivot bolt 129 (see Fig. 17), which provides sufficient play to permit adjustment for transverse alignment of the power unit.

The power unit 130 is a duplicate of unit 110, except that its jackshaft 131 is modified to connect with both intermediate shafts 132, 133.

The power unit 140 which drives pumps 141, 142 is shown with the engine partly broken away to show the wedges used as a means of effecting and locking transverse adjustment of the power unit. Its jackshaft 143 carries free sprockets 144, 145, which may be connected to the shaft by clutches 146, 147. Sprocket 144 has driving connection with the pump sprocket 148 and the sprocket 145 has driving connection with the pump sprocket 149.

The bed structure, as shown in Figs. 12, 13 and 16, comprises power unit bed members 124, 124 held in parallel, spaced relation by end angles 150, 151 and cross braces 152, 153 (not shown in Fig. 1). The bed members and end angles are bolted together through corner angles 160, 160 and with the braces 152, 153 make up a unitary structure which can be transported intact or disassembled.

The pumps 141, 142, being on practically the 70 same plane as the power units, may be mounted on bed members 156, 156 facilitating assembly. The hoist 121 is usually mounted on the drilling platform.

One of the intermediate shafts 132 is shown in 75

section in Fig. 18. Spiders 134 are keyed to jackshafts 115 and 131 and to one end of shaft 132. To these spiders are bolted flexible discs 135 in a well known manner, so that the parts 134, 135, 5 134 form a universal joint. The other end of the shaft 132 is reduced in diameter at 191 and is supported and turns freely in a bearing 192 in the spider 136, which is provided with the clutch jaws 137. A sliding jaw clutch 138 is 10 splined upon the shaft 132 and shifted by the collar 139 through suitable levers (not shown). After disconnecting from the flexible discs, the spider 136 and the jaw clutch 138 can be slid back upon the shaft 132 to provide clearance for 15 assembling when the jackshafts 115 and 131 are in place.

It is evident that this assembly will operate satisfactorily with a considerable degree of misalignment and a reasonable variation in spacing 20 of the jackshafts.

In assembling the plant, the bed structure would be put in place, either as a unit or bolted together on the job, the power units would be slid onto their bed members and adjusted to bring the jackshafts into substantial axial alignment and the intermediate shafts put in place, completing the assembly. If the pumps are provided with bed members 156 attached to the main bed structure, their addition to the assembly is 25 equally rapid.

In this arrangement, power unit 130 may be used as a spare unit substituting for or combined with either or both the other units, or it may be held idle in reserve.

It is evident that this invention produces a power plant which can be rapidly assembled. Given a surface reasonably level, the component units can be assembled into place with military precision. Driving strains between the parts are 30 self contained within the bed structure making expensive sub-foundations unnecessary. The jackshaft units each having only two self-aligning bearings will operate under any reasonable degree of distortion and the intermediate shaft 35 can accommodate sufficient misalignment to make the placing of the jackshaft units a matter of minutes. Correct spacing of the units is assured by the bed structure.

The plant is separable into easily transported 40 units and can be quickly reassembled for operation.

The spare engine with its independent, selective clutch controlled drive renders this power plant flexible, so that it is quickly adapted to 45 perform any of the required operations.

What I claim is:

1. A power plant, a flexible foundation therefor, a pair of jackshafts mounted thereon and

substantially in alignment with each other, a transmission shaft therebetween, a flexible driving connection keyed to one end of said shaft and a second flexible driving connection rotatably mounted on the other end of said shaft and connected to one of the jackshafts, clutch means for coupling the transmission shaft to said jackshaft. 5

2. A power plant, a jackshaft therefor, a bearing at each end thereof, a second power plant, a 10 jackshaft therefor, a bearing at each end thereof, an intermediate propeller shaft connecting said jackshafts together through two flexible joints at each end, which are supported by adjacent end bearings of said jackshafts, coupling 15 and uncoupling means on said propeller shaft.

3. A power plant, a flexible foundation therefor, two jackshafts in approximate axial alignment mounted thereon, a transmission shaft therebetween, comprising a hollow shaft engaging 20 with one of the jackshafts and supported thereby, a smaller shaft rotatably mounted within said hollow shaft and engaging with and supported by the other jackshaft, a dog clutch slidably mounted on said smaller shaft and adapted 25 to engage with the end of the hollow shaft, for the purpose described.

4. In a power plant, as set forth in claim 3, in which the connections between the jackshafts and the transmission shaft consist of universal 30 joints.

5. A portable power plant comprising a flexible foundation of structural steel sections, a plurality of prime movers mounted thereon, a plurality of jackshafts in operative relationship therewith 35 also mounted thereon, transmission shafts connecting the jackshafts together and supported thereby.

6. A portable power plant comprising a flexible foundation therefor, two jackshafts axially 40 aligned and mounted thereon, a transmission means therebetween consisting of a hollow tubular shaft enclosing another shaft, flexible driving connections to each of said jackshafts from one of said shafts, clutching means for connecting 45 the tubular shaft with the shaft enclosed therein.

7. A portable power plant comprising a flexible foundation therefor, two jackshafts axially aligned and mounted thereon, self aligning bearings therefor, a transmission means therebetween 50 consisting of a hollow tubular shaft enclosing another shaft, flexible driving connections to each of said jackshafts from one of said shafts, clutching means for connecting and disconnecting the tubular shaft with the shaft enclosed 55 therein.

JOHN RIISE.
